TANK CAP TOOL

Joseph V. Milo, Union, N. J.

Application April 18, 1949, Serial No. 2,091

Term of patent 7 years

(Cl. D54—16)

To all whom it may concern:

Be it known that I, Joseph V. Milo, a citizen of the United States, residing at Union, in the county of Union, and State of New Jersey, have invented a new, original, and ornamental Design for a Tank Cap Tool, of which the following is a specification, reference being had to the accompanying drawing, forming part thereof.

Fig. 1 is a perspective view of a tank cap tool, showing my new design;

Figs. 2 to 5 inclusive are end elevational views of the four elements of the tool; and

Fig. 6 is a sectional view taken on line 6—6 of Fig. 1.

I claim:

The ornamental design for a tank cap tool, as shown.

JOSEPH V. MILO.
